IMPRINTING OR EMBELLISHING APPARATUS

Jay C. Gangel, Oceanside, N. Y., assignor to Merrill-Niel Co., Inc., New York, N. Y., a corporation of New York

Application October 18, 1937, Serial No. 169,557

4 Claims. (Cl. 101—9)

This invention relates to imprinting or embellishing apparatus and provides improvements therein.

Many stores catering to well-to-do customers, 5 foster their trade by an appeal to the individuality of the customer. For example, the customer's monogram is imprinted on goods which he purchases. Apparatus heretofore in use for this purpose is too expensive for the general run of 10 storekeepers, and the service of imprinting or embellishing goods to meet the individual desires or tastes of the customer is thus restricted.

The present invention provides an imprinting or embellishing apparatus of a very simple construction, which can be made at low cost, and 15 sold at a price which will permit of popular use amongst storekeepers. The invention further provides an apparatus capable of use for imprinting or embellishing a wide variety of articles, 20 which is readily adjustable to attain the most economical use of the printing ribbon, and which facilitates and speeds the work of imprinting small articles and those which are somewhat awkward to handle in carrying out the imprinting 25 operation.

An embodiment of the invention is illustrated in the accompanying drawings, wherein:

Fig. 1 is a view in side elevation of the apparatus.

Fig. 2 is also a view in side elevation showing a 30 part of the apparatus from the opposite side of that shown in Fig. 1.

Figs. 3 and 4 are top plan views of a part of the knock-out mechanism, the parts being shown 35 in two different positions of operation.

Fig. 5 is a view of the apparatus in front elevation.

Fig. 6 is a view partly in section and partly in 40 side elevation of the plunger and its head equipped with heating means.

Fig. 7 is a cross-section of a chase containing 45 a printing form, adapted to be attached to the head shown in Fig. 6.

Referring to said drawings, numeral 10 designates a frame, which is advantageously of the 50 form shown. That is, the frame has a goose-neck portion 12 which overhangs a bed 14, and provides maximum access to the space beneath the plunger. The neck-portion 12 may have an enlargement 16 thereon, which has a vertical bore 18 therethrough which supports and guides a reciprocating plunger 20 therein. The bore 18 and the plunger 20 are conveniently round, the plunger 20 being longitudinally slotted as indicated at 55 22 to receive a pin 24 carried by the head portion

16, which prevents turning of the plunger 20. The plunger 20 is preferably provided with a head 26, which head is preferably provided with suitable means for heating. The heating means preferably comprises a small electrical resistance unit 5 28 which is held within a recess 29 in the head 26 as shown most clearly in Fig. 6. A thermostat 30 may be provided for regulating the temperature of the head 26.

Numeral 33 designates a printing form, and 10 this advantageously forms a separate unit or combination of units, placed and held in a chase 35, which chase is also preferably formed separately from the plunger head 26 and provided with means, as a dove-tail portion 37 fitting within a dove-tail groove 38 for fastening the chase to the head. The head 26 and the chase 35 are of metal and the head when heated imparts heat to the chase and printing form 33 therein. 39 15 designates a clamp for fastening the printing 20 form 33 in the chase. Numeral 40 designates a set-screw mounted on the head and adapted to set against the chase 35 to prevent movement of the chase when connected to the head 26 through the dove-tail connections 37, 38. 25

Means are provided for reciprocating the plunger 20. These means advantageously comprise an oscillatory shaft 45 mounted in a bore in the enlarged portion 16 of the frame, and a pinion 47 fixed to the shaft 45, and arranged to engage a 30 rack 49 on the adjacent side of the plunger 20. A handle 50 attached to the shaft 45, at one side of the enlarged portion 16, serves to oscillate said shaft, and thereby, through the pinion 47 and rack 49, translate the oscillatory movement of 35 the shaft 45 to reciprocatory movement of the plunger 20. The plunger 20 is normally pressed toward its upper position by a spring 53, one end of which hooks on a pin 54 on the shaft 45, and the other end of which is held by a screw 56 on 40 the side of the enlarged portion 16 of the frame.

The imprint or embellishment is usually done in color, and to this end an inking ribbon 60 is interposed between the printing form 33 and the article. The ribbon 60 carries a composition containing a colored pigment, which pigment is transferred to the article under the action of the plunger 20 and the printing form 33 carried thereby. The composition is usually of a character which requires heat for effecting a transfer, and this heat is supplied by the heating unit 28 and the metal parts 26 and 35 which conduct the heat to the printing form 33. Means are provided for leading the ribbon 60 beneath the plunger 20 and the printing form 33 thereon, and for taking it 55

up intermittently to provide fresh portions for the action of the printing form. This means comprises a spindle 62 rotatably mounted in a boss 64 on an arm 66 fastened to a side of the portion 16 of the frame, as indicated at 68, Fig. 2. A spool 70 may be fastened to the spindle 62, to rotate therewith, as by means of a fastening screw 72. The spindle 62 (and with it the spool 70) is intermittently rotated by suitable means, which means are advantageously as follows: A ratchet wheel 75 is fastened on the shaft 62, and this ratchet wheel is engaged by a pawl 77 pivoted on a lever arm 79, which lever arm pivots on the spindle 62, as indicated at 81, Fig. 5. A rock-arm 85 is fastened on the oscillatory shaft 45, at one side of the enlarged portion 16 of the frame, and the rock-arm 85 and the free end of the arm 79 are connected by a link 86. The rocking movement of the arm 85, when the shaft 45 is oscillated through the action of the handle 50 and the spring 53, through the action of the link 86, lever-arm 79, pawl 77 and ratchet wheel 75, acts to intermittently rotate the spindle 62 and take-up successive lengths of the ribbon 60 on the spool 70. The radius of the rock-arm 85 on the oscillatory shaft 45, is advantageously made adjustable. To this end the end of the shaft 45 may be slotted as indicated at 90, and the said arm slidably fitted therein. The arm 85 is also preferably slotted as indicated at 92, and a clamping screw 95 which screws into the end of shaft 45, passes through the slot 92 in arm 85, and when the clamping screw 95 is tightened it serves to fasten the arm 85 to the shaft 45. By loosening the clamping screw 95, the radius of the arm 85 may be lengthened or shortened, and thereby the throw of the lever 79 and the amount of the rotation of the spool 70 adjusted. This adjustment provides for economy in the use of the inking ribbon 60. The width of the printing portion of the printing form 33 varies for different printing forms, and the adjustment of the radius of the arm 85 by the means just described, permits of the spool 70, at each rotation, taking-up just sufficient of the ribbon 60 to provide a fresh portion beneath the imprinting portion of the printing form after each printing operation.

The ribbon 60 is usually supplied from a spool 100, and a pin or shaft 102 may be provided for supporting the spool 100. The pin 102 may be fixed at one end to an arm 104 which latter may be fastened to the goose-neck portion 12 of the frame, as seen in Fig. 1. The spool 100 in the form of construction illustrated, turns on the pin 102 against a slight resistance.

Numerals 106, 107 designate ribbon-guides. These are advantageously in the form of rods having right angle ends 109, 110, 111, 112. The ends 109-111 fit in bores in the portions 12 and 16 of the frame, and are held therein, in any of a number of different positions of adjustment by set-screws 114, 115. The ends 110 and 112 are in sliding contact with the ribbon 60.

It is highly important to obtain uniformity of the imprints or impressions. For example, in embellishing a deck of cards with a monogram, uniformity is of great importance. Different operators, and the same operator at different operations, apply the printing form to the article with different pressures. To avoid these differences, an adjustable plunger-stop 120 is provided, which stop is advantageously in the form of a screw having threaded engagement with a plate 122 fitted on the upper part of plunger 20 and

fastened thereon, as indicated at 123. The stop 120 is so located that its end abuts on the top of the portion 16 of the frame on the down-stroke of the plunger at a position where its downward movement is to be arrested.

Knock-out means are advantageously provided for displacing articles after being imprinted. This means comprises a pusher 130 arranged to operate on the article. The pusher 130 may be, as here shown, a rod supported by blocks 132, 133, and axially movable therein in a plane parallel to the face of the bed 14 of the frame. The pusher 130 is pivotally connected to an arm 135 pivoted to the bed (or to a plate thereon), which arm has a cam 137 thereon.

The cam 137 is acted on by an arm 140 attached to the oscillatory shaft 45, preferably at the end thereof opposite to the arm 85. For this purpose the shaft 45 may be slotted as indicated at 143, the arm 144 fitting in the slot, and being fastened to the shaft 45 by a clamping screw 145, for example.

The arrangement of the arm 140 is such that it contacts with the cam 137 to retract and release the arm 135 and the pusher 130 connected thereto during the upward or rising movement of the plunger 20. A spring 150 is compressed during the retraction of the pusher 130, and when the pusher is released the spring projects the pusher against the article. The pusher 130 is preferably provided with a cushion-stop 155, which may be of rubber. When the cushion-stop 155 strikes against the block 132, the pusher will move forward slightly after the contact is made between the cushion-stop 155 and the block 132, and then will be retracted slightly under the expanding action of the compressed rubber. In this way the pusher 130 may perform the function both of a locating device and an ejector or knock-out. As shown in the drawings, the end of the pusher extends axially into a holder 160, grooved to receive a lead pencil to be imprinted. To enable the arm 140 to pass the cam 137 on the oscillation of the shaft 45 corresponding to the downward or impression stroke of the plunger 20, the said arm 140 is provided with a toe-piece 163, pivoted to said arm in such manner as to yield and pass over the cam 137 when the arm 140 swings to the right in Fig. 1, and which moves against a pin 165 which prevents it from yielding on the return movement, and on each return movement the toe 163 strikes against the cam 137 and forces it to move the lever 135, in the manner heretofore described.

Résumé of operation

When it is desired to imprint or embellish an article, as the pencil shown in the drawings, the pencil is placed in the holder 160 against the end of the pusher 130. The initial position of the parts is that shown in Fig. 1. The handle 50 is then turned toward the operator or to the left in Fig. 1. The plunger 20 is forced downward through the action of shaft 45, gear wheel 47, and rack 49, bringing the printing form 33 against the pencil, with the inking ribbon 60 interposed. The pressure of the printing form 33 (together with the heat in appropriate cases) effects the transfer of the outline of the printing form to the pencil. The lower position of the plunger and the printing form 33 thereon is regulated by the stop 120, so as to obtain a substantially uniform impression on each operation of the apparatus.

When the operator releases the handle 50, the

spring 53 oscillates the shaft 45 in the opposite direction raising or lifting the plunger 20 and the printing form 33 through the action of the gear 47 and rack 49.

5 As the shaft 45 oscillates, the two rock-arms 85 and 140 thereon move forward toward the positions shown in Figs. 1 and 2.

As the rock-arm 85 moves forward, it swings the lever arm 79 forward, and the pawl 77 thereon, through the ratchet wheel 75, rotates the spindle 62 a distance of one or more teeth corresponding to the radial setting of the rock-arm 85. The radial setting of the rock-arm 85, and the consequent action of the lever arm 79, pawl 77, ratchet wheel 75, and spindle 62 is such that the spool 70 on the spindle 62 will take up enough of the inking ribbon 60 to draw a fresh portion of the ribbon 60 under the face of the imprinting portion of the printing form 33. Thus the machine may be adjusted to imprinting means of varying width, with a maximum economy in the use of the inking ribbon 60.

When the rock-arm 140 moves forward, as previously described, the toe 163 thereon strikes 25 against the cam 137 on the lever 135 and moves it to retract the pusher 130. While moving forward, the toe 163 on rock-arm 140 moves off of the cam 137 and releases the arm 135, and when so released the pusher 130 is projected toward the 30 pencil, the cushion 155 yielding to enable the pusher to strike the pencil a light blow, and thereby knock-out or eject the pencil.

The apparatus may receive other embodiments than that herein specifically illustrated and described.

What is claimed is:

1. Apparatus of the character described, comprising a frame, a reciprocating plunger, a head thereon for supporting a printing form, an oscillatory shaft having projecting ends, a pinion on said shaft, a rack on said plunger for imparting

reciprocating movement to said plunger, a handle near one end of said oscillatory shaft, a spindle for supporting a spool, guides for leading an inking-ribbon beneath said plunger to a spool on said spindle, and means for intermittently rotating said spindle to take up said ribbon on said spool, comprising a ratchet-wheel on said spindle, a lever-arm having a pawl thereon for intermittently rotating said ratchet-wheel, a rock-arm on said oscillatory shaft, and a connection between said rock-arm and said pawl-carrying lever arm. 5

2. Apparatus of the character described according to claim 1, wherein said rock-arm is adjustable toward and from the axis of said oscillatory shaft, so that the throw of said pawl-carrying lever may be adjusted to thereby adjust the take-up of the inking-ribbon on the spool at each actuation of the lever-arm to an amount corresponding approximately to the width of the imprinting part of the printing form. 10 15 20

3. Apparatus of the character described according to claim 1, further including knock-out means, said latter means comprising a rock-arm on said oscillatory shaft, a pusher, and means co-acting with said last named rock-arm to actuate said pusher on the rising movement of said plunger, to eject an article. 25

4. Apparatus of the character described according to claim 1, further comprising a knock-out means, said latter means comprising a rock-arm on said oscillatory shaft, a pusher, a lever for moving said pusher, a cam on said lever co-acting with said last named rock-arm, on the rising movement of the plunger, to retract 30 35 and release said lever to actuate said pusher to eject an article, said last-named rock-arm having a pivoted toe-piece arranged to yield and pass idly over said cam on the downward stroke of said plunger.

JAY C. GANGEL. 40
